UNITED STATES PATENT OFFICE.

FRANK E. WILDER, OF SALEM, ASSIGNOR TO OSCAR M. ANGIER, OF BOSTON,
MASSACHUSETTS.

TYPE-WRITING MACHINE.

SPECIFICATION forming part of Letters Patent No. 447,720, dated March 3, 1891.

Application filed July 22, 1889. Serial No. 318,216. (No model.)

To all whom it may concern:

Be it known that I, FRANK E. WILDER, of Salem, in the county of Essex and State of Massachusetts, have invented certain new and useful Improvements in Type-Writers, of which the following is a specification.

The object of my invention is to furnish a simple, inexpensive, light, and reliable type-writing machine that may be operated as rapidly and in a similar manner by the keys, and also just as practically, as the more expensive and bulky machines.

Another object of my invention is to furnish such a machine that will write with the paper in a horizontal position and under the eye, so that the writing can be read the most readily without having to previously lift up any mechanism and while the writing is being done.

In the accompanying drawings, forming a part of this specification, Figure 1 illustrates a plan view of my improved type-writing machine. Fig. 1* is a back view of the same. Fig. 2 is a transverse vertical section, taken through the line $x-x$ of Fig. 1. Fig. 3 is a similar section through the line $y-y$ of Fig. 1, but with the paper-carriage and its connecting parts removed. Fig. 4 is an end view of the left-hand end of the paper-carriage and its connecting parts. Fig. 5 represents in detail the mechanism for drawing down the type cylinder or spools. Fig. 6 is a plan of the back portion of the machine, the front portion and keys being broken away and the paper-carriage, with its connecting parts, removed. Fig. 7 is a longitudinal section through the line $z-z$ of Fig. 6. Figs. 8 to 12, inclusive, are details.

Similar letters and numerals represent like parts in all the figures.

A is the frame of the machine, which supports the working mechanism, and B is the longitudinal back bar of said frame forming the rail, upon the upper edge of which the rollers of the paper-carriage are adapted to travel. The upper portion of the rail B extends outwardly, forming a flange having a longitudinal shoulder a parallel to the top of said rail.

C is the frame for holding the paper-cylin-

der, inking-ribbon, &c., and constitutes the traveling paper-carriage. Said carriage supports the ordinary revolving cylindrical platen D, to one journal of which is secured the platen knob or handle b , and to the other journal or opposite end of the platen is secured the ratchet c. The grooved carriage rollers or wheels d are journaled to the back of the carriage C, and are adapted to ride over the rail B.

1 is the front bearing rod or rail of the paper-carriage, which rests upon and is adapted to ride over a roller 2, journaled on the frame A, and a lug 3, extending over said roller and rail, serves as a guide for the rail.

4 are two lateral pins projecting from the paper-carriage, one at each end, over which the ribbon l passes and is stretched.

A plate E, having projecting ends e , extending downwardly from the same, is removably attached to two lugs or projections f , extending outwardly from the carriage C. The ends e are bent inward, forming lugs g , which extend under and against the shoulder a . Said plate E, with its lugs g , serves as a guide for the paper-carriage and to keep it firmly in its position on the rail B. The plate E may be adjustably attached to the carriage C by means of screws and slotted holes in said plate.

Extending downwardly from the carriage C are two lugs h , which form journal-bearings for a rock-shaft F. Two arms i are secured to said shaft and extend inwardly from the same, and the rack G is supported longitudinally with the carriage by said arms to which said rack is secured. An arm H extends upwardly and outwardly from the shaft F, by which arm the rack is adapted to be lifted. The rack G may either be held down in its normal position by its own weight or a spring may be used for this purpose. The spring line-space lever I to which the pawl or dog j (for operating the platen-ratchet c) is attached, extends outwardly (see Figs. 1, 1*, 2 and 2) and in front of the arm II, and said arm will bear against the lever I, so that when the latter is pushed down it will carry the arm H with it, and thus raise the rack G.

The ribbon-reels J J are hung on journals

 & *k*, which extend laterally in front of the carriage *C*, and with the ribbon *l* extending longitudinally over the top of the platen. Coil tension-springs *m m* may be inserted between the reels *J J* and adjusting-nuts *n n*, if so desired. An adjusting-screw *o* extends through the back of the carriage *C*, with its end abutting against the lower arm *b* of the lever *I*, and serves to regulate the play of said arm in a backward direction and the forward play of the dog *j*.

A pinion *K*, having a ratchet *L* secured to its back surface, is loosely journaled upon the frame *A* in such position that when the carriage *C* is in proper position, with its rollers *d d* on the rail *B*, the rack *G* will engage with said pinion. When the rack *G* is lifted by the arm *H* out of engagement with the pinion *K*, the paper-carriage can readily be slid back and forth. A spring-actuated arm *M*, pivoted longitudinally to the frame *A*, has a pivoted dog or pawl *q*, which engages with the ratchet *L*, the actuating-spring of said arm tending always to bear the dog *q* down against said ratchet. The free end of said arm *M* is provided with a pin or projection *r*, which is adapted to engage with the rack *G* when said pin is lifted and to hold said rack firmly until the pin releases it.

32 *N* is a rod extending longitudinally the entire length of the machine, and which constitutes the fulcra of all of the key-levers *O* and *P*, which are levers of the first class.

35 *Q* and *R* are two longitudinal bars, each of which is pivotally connected with the rod *N* by right-angled backwardly-extending arms *s*, the bar *Q* being just in the rear of the bar *R*. The key-levers *O* of the forward and lower row of keys *S* extend back and under the bar *Q*, and the key-levers of the back and upper row of keys *T* extend back only under the bar *R*, said levers *O* and *P* bearing against the under side of the bars *Q* and *R*, respectively.

45 A bell-crank lever *S^x* is pivoted to the rod *N* about half-way between its ends, the upper arm of said lever having a backward projection *S^x* extending over the bars *Q* and *R*, and with downwardly-extending pins or projections bearing on the top of said bars. The lower arm of the lever *S^x* is provided with a lateral lug *f*, on which the space-key arm *U* rests, said arm being loosely hung upon the rod *N* and not extending back of the same.

55 A bell-crank lever *V* is also pivoted on the arm *N* and has its upper arm *u* attached to the lever *S^x*, its lower arm *v* extending backward and under the arm *M*. When the space-key arm *U* is depressed, the arm *v* of the lever *V* will raise the arm *M* and the dog out of engagement with the ratchet *L*, and when said arm is released the dog *q* will fall back, engaging with the next tooth of the ratchet *L*, and thus move the rack *K* and the paper carriage to the left the space of one letter.

65 *W* is a bar, upon which is secured or cast at right angles to the same a tube or cylinder

X, and this bar and cylinder are supported by journal-bearings on either end of said bar on raised supports *Y Z* near the center of the machine, so that the cylinder *X* will be transverse to the machine. Two arms *w w* extend forward from the bar *W*, and one of said arms is connected by a link *z* to the forward end of a spring bell-crank lever *A'*, pivoted to the rod *N*, the backward and upper arm of said lever *A'* (see Fig. 5) extending over the bars *Q* and *R* in a similar manner to the lever *S^x* and with similar bearing points or projections.

80 The cylinder *X* forms a long stationary bearing for supporting the shaft or spindle *B'* of the type-cylinder *C'*, and when either of the bars *Q* or *R* is raised by any of the key-levers the inner arm of the lever *A'* will be depressed and through the link *z* draw down the bearing *X* and the type-cylinder *C'* onto the ribbon *l* and against the paper and platen. When the key-lever is released, the spring-lever *A'* will return to its normal position, and the bearing *X* and the type-cylinder *C'* will be raised again.

85 The type is placed or arranged on the periphery of the cylinder *C'* in a somewhat similar manner to that of the Crandall type-writer, and it is therefore necessary to have mechanism for revolving the cylinder in order that the type corresponding with the key that is struck may be directly over the ribbon. The mechanism as above briefly stated is as follows:

90 *D'* is a pinion, which fits into a recess in the bar *W*. The shaft *B'* of the type-cylinder *C'* extends loosely through said pinion, and is keyed to said shaft by a feather fitting into a longitudinal groove *a'* in the shaft. By this means the shaft *B'* may freely have longitudinal play in the pinion *D'*; but when the latter revolves the shaft *B'* and cylinder *C'* will also have to revolve.

95 *E'* is a vertical segmental gear fixed to the rocking horizontal shaft *b'* and engaging with the pinion *D'*.

100 *F'* is a smaller segmental bevel-gear, also fixed or keyed to the shaft *b'* and extending laterally from the same. A similar segmental gear *G'* engages with the gear *F'*, and is secured to a rock-shaft *H'*, extending the length of the machine.

105 *I' I' I'* are downwardly-extending arms keyed to the rock-shaft *H'* and passing between the key-levers *O* and *P*. The lower end of each arm *I'* is provided with lateral lugs extending each side of the arm or a pin *c'*, passing through said arm. Each key-lever *O* and *P* has a cam-shaped slot *d'*, with curved walls extending up from the lower edge of said lever, and the lever when depressed brings one of the walls or edges of the cam-shaped slot into contact with one of the pins *c'* on the arm *I'* bearing against said pin, so as to rock the arm *I'*, shaft *H'*, and racks *G'* and *F'*, and thus rotating the pinion *D'* and the type-cylinder *C'*. The arms

I' are keyed at such an angle on the shaft II' in relation to the type on the cylinder C' that when a particular key is depressed it will immediately bring its corresponding type on the cylinder C' directly over the inking-ribbon. It will be understood that the type-cylinder C' does not return to a central or normal position after a key-lever is depressed, but remains in the position said key-lever left it, and the cam-slots d' are of such shape and the arms I' set at such an angle thereto that any key will bring the cylinder to its proper position, no matter in what position the preceding key had left it.

15 I will now proceed to describe the mechanism for moving the type-cylinder C' forward and backward in order that a type from any row on said cylinder may be brought into position over the inking-ribbon.

20 J' is a vertical plate, having two horizontal and longitudinal slots e' f', (see Fig. 3,) and g' h' are headed screws or pins extending through said slots and into lateral lugs of the frame A, thus allowing the plate J' to have 25 longitudinal play.

The shaft B' of the cylinder C' has keyed upon it a pinion i' for a purpose hereinafter to be described, and j' is a loose sleeve encircling the shaft B' and held from longitudinal play on said shaft by means of a short collar k' and a binding-screw passing through the same and bearing against said shaft. The sleeve j' is connected by a link l' to a vertical plate or bar K', which is secured to the 35 plate J'. A backwardly-projecting bar m' extends from the plate K', and has a narrow upper edge, which is adapted to engage with the teeth of the pinion i' when the latter and the type-cylinder C' are depressed, thus locking 40 said type-cylinder and holding it firmly while the type is striking the ribbon and paper. A lug having a vertical slot n' projects upward from the front of the lug 3, and said slot serves as a guide for the bar m'. (See 45 Fig. 8.) L' is a spring-lever which is pivoted to the top of the frame A and with the outer end of its longer arm bearing against a shoulder o' on the top edge of the plate J'.

M' (see Figs. 1 and 2) is an L-shaped lever 50 loosely journaled on the rod N near its left-hand end, the short upper arm of said lever bearing against the back edge of the short arm of the lever L' and the front end of the lever M' extending to the front of the machine near the keys, and also provided with a key. An arm N' is also loosely pivoted on the rod N by the side of the lever M', and has a lateral lug p' extending from its top edge and resting on the top edge of said lever M', so that when the arm N' is depressed the lever M' will also be carried down with it. Two shoulders q' r' in the front of the frame A serve as stops to the downward play of the lever M' and arm N', respectively. The 65 arm N' extends in front and beyond the lever M' and is provided with a key similar to said lever. When the arm N' is depressed,

it carries the lever M' down far enough, so as to force the type-cylinder C' forward a slight distance through the instrumentality of the 70 lever L', plates J' and K', and link l', and when the lever M' is depressed until it strikes the stop q' said lever carries the type-cylinder forward still farther. Said lever M' and arm N' are so regulated with the parts connecting them with the type-cylinder C' that when the arm N' is depressed to its fullest extent the capital-letters type on the third and fourth rows from the back end of the cylinder will come over the inking-ribbon, and 80 when the lever M' is depressed to its fullest extent the figures and punctuation-marks type on the last two or forward rows of the cylinder will come over the inking-ribbon.

O' and P' (see Fig. 3) are two bell-crank 85 levers loosely pivoted side by side to the rod N and with their backward ends s' t' secured to the top of the bars Q and R, respectively. The lower forward portions of said levers Q' and P' are provided with cam-shaped slots u' 90 and v' similar to those of the key-levers, and said slots are adapted to engage with three pins w', extending laterally from the lower portion of the plate J'. The object of these cam-slotted levers O' P' is to bring the proper 95 row of characters on the cylinder C' (there being two rows for each set of characters) above the ribbon and the portion of the platen to be struck simply by the depression of the required key, the action being performed from 100 the key to the bar Q or R to the lever O' or P', and thence to one of the pins w', the plates J' K', link B', and the type-cylinder C'.

Q' Q' are two levers loosely journaled on the arms w with the rear and shorter arms of 105 said levers extending under and resting against the lower edge of the bar W. The forward and longer arms of the levers Q' Q' extend as far as the type-cylinder C', where they are formed into loops, through which the 110 inking-ribbon l passes.

I do not limit myself to the precise construction as hereinbefore set forth, as the different features may be somewhat varied or modified without altering my invention; but 115

What I claim is—

1. In combination with the paper-carriage and its rack, the pinion K, ratchet L, spring-lever M and its dog, the projection r, and means for raising the lever M, as set forth. 120

2. In combination with the paper-carriage and its rack, the pinion K, ratchet L, spring-lever M and its dog, and a space-lever for lifting said lever M, all as set forth.

3. In combination with the paper-carriage 125 and its rack, the pinion K, ratchet L, spring-lever M and its dog, the lever S^x, having the lug t, and a space-lever for bearing down said arm and lifting the lever M, as set forth.

4. In combination with the ratchet L, 130 spring-lever M and its dog, the levers S^x and V, attached at their upper arms, and means for raising the upper or backward arm of the lever S^x, all as set forth.

5. In combination with the ratchet L, spring-lever M and its dog, the levers S^x and V, attached at their upper arms, a pivotal bar or bars bearing against the undersides of said upper arms, and a space-lever for lifting said bar or bars, all as set forth.
6. In combination with the type-cylinder and its shaft, a bar extending transversely across and attached to the same and pivoted at its ends to two standards, an arm projecting from said cross-bar, a connecting-link extending from said arm, and a lever for bearing down said link, all as set forth.
7. In combination with the type-cylinder and its shaft, a bar extending transversely across and attached to the same and pivoted at its ends to two standards, an arm projecting from said cross-bar, a connecting-link extending from said arm, the lever A', a pivotal bar or bars for bearing against the underside of said lever, and the key-lever for lifting the same, all as set forth.
8. In combination with the type-cylinder having a longitudinal shaft and a pinion keyed to the same, a segmental gear for engaging with said pinion, the shaft b', segmental gears E' and G', shaft H', arms I', and means for rocking the same, all as set forth.
9. In combination with the type-cylinder having a longitudinal shaft and a pinion keyed to the same, the segmental gears E' F' G', shaft H', arms I', having the projections o', and the key-levers having the cam-slots d', all as set forth.
10. In combination with the type-cylinder having a longitudinal shaft and a pinion keyed to the same, the series of levers having the cam-slots d', the shaft H', a series of hanging arms secured to said shaft and having bearing-surfaces for said cams, and a series of gears connecting said shaft with the pinion on the type-cylinder shaft, all as set forth.
11. In combination with the type-cylinder pivotally supported in a lateral direction, the pinion i', and bar m' longitudinally movable in unison, all substantially as and for the purpose set forth.
12. In combination with the type-cylinder supported in a lateral direction, with its shaft having longitudinal play, a vertical horizontally-sliding plate connected with said cylinder, and a spring-lever for operating the same, all as set forth.
13. In combination with the type-cylinder supported in a lateral direction, with its shaft having longitudinal play, a vertical horizontally-sliding plate connected with said cylinder, a spring-lever for operating the same, and a key-lever for operating said spring-lever, all as set forth.
14. In combination with the type-cylinder supported in a lateral direction, with its shaft having longitudinal play, a vertical horizontally-sliding plate connected with said cylinder, lateral projections on the under side of said plate, a lever having a cam-slot in its under side for engaging with said projections, and the key-lever for operating said cam-lever, all as set forth.
15. In combination with the key-lever, a lever operated by said key-lever and having cam-slots in its under side, a sliding plate having bearings for engagement with said slot, and a connection between said plate and the type-cylinder, whereby the latter is slid backward and forward, all as set forth.
16. In combination with the type-cylinder and the sliding plate connected with the same, the bar m', and the slotted guide n', all as set forth.
17. In combination with the inking-ribbon, the type-cylinder supported in bearings over the same, arms projecting from the cross-bar support of the type-hammer, and the levers Q' Q', having loops at the ends of their outer arms, through which said ribbon passes, all as set forth.
- In testimony whereof I have signed my name to this specification, in the presence of two subscribing witnesses, this 1st day of July, A. D. 1889.
- FRANK E. WILDER.
- Witnesses:
- ARTHUR W. CROSSLEY,
A. D. HARRISON.
